[57] **CLAIM**

The ornamental design for a water cooler cabinet, as
shown and described.

DESCRIPTION

FIG. 1 is a top, front and left side perspective view of a
water cooler cabinet showing my new design;

FIG. 2 is a left side elevational view thereof; the side
opposite is a mirror image thereof;

FIG. 3 is a front elevational view thereof;

FIG. 4 is a bottom plan view thereof;

FIG. 5 is a top plan view thereof; and

FIG. 6 is a rear elevational view thereof.

FIG. 1

FIG. 2

FIG. 3

FIG. 4

FIG. 5

FIG. 6
